UNITED STATES PATENT OFFICE.

CHARLES G. LOHMAN, OF ST. LOUIS, MISSOURI, ASSIGNOR TO THE EDWIN F. GUTH COMPANY, OF ST. LOUIS, MISSOURI, A CORPORATION OF MISSOURI.

CANOPY LIGHTING FIXTURE.

Application filed July 15, 1925. Serial No. 43,734.

My invention relates to the art of illumination, particularly that portion of the art wherein mechanical elements are co-ordinated in a lighting fixture unit, to intercept, 5 modify and redirect, the rays of light issuing from the source, so as to be delivered to a working plane in a certain desirable manner.

The object of my invention is to provide a lighting fixture unit to enclose the light 10 source which, when the parts are assembled, will effectually conceal all securing means and will contain no exposed screws, bolts or any similar elements which will detract from the general appearance of the unit.

15 A further object is to provide in a lighting unit a reflector and reflector flange, comprised of one piece, preferably of metal, so formed as to provide co-operating means by which it may be secured to the outlet box, 20 and also will provide means for holding the bowl or globe which is designed to surround the lamp.

A further object is to provide such a reflector flange as will also provide means for 25 seating of the socket.

A further and most important object is to provide such a reflector flange which, when made of metal, will be of one piece which may be stamped, thereby providing 30 simplicity of construction and a material reduction in the ordinary expense that would be attendant upon the manufacture of such a device.

A yet further object is to provide such a 35 reflector flange which will have a double spaced, wall at its lower portion of said walls functioning for the mounting and stabilizing of securing means for the bowl.

A yet further object is to provide in a 40 lighting fixture of the class described, securing means for the bowl, comprising two stationary lugs and a movable lug held on spring tension, and of a cam construction, which will make it adaptable to bowls of 45 varying sizes.

My invention consists of certain details of construction in which

Fig. 1 is a vertical sectional view, a portion 50 of the globe being shown in elevation;

55 Figure 2 is a cross section on line 2—2 of Fig. 1, with the shade left off.

Fig. 3 is a fragmentary detail view of a modified form of fastening means.

Referring to the accompanying drawings, 55 my reflector flange comprises a one piece

structure with the horizontal inner section 10 formed to function as a reflector, with sides 11 depending therefrom, and thence turning upwardly, as shown at 12, and flaring outwardly to form the canopy which 60 terminates in the ring 13. In the center of the reflector plate is an orifice 14 designed to receive the mating parts 15 and 16 of a separable socket, the part 15 having the neck 17 which extends through the orifice in the 65 reflector plate, thus providing means for seating the socket in the reflector plate, as shown. The reflector plate is also provided with orifices 18 designed to receive screws 19 which engage screw threaded orifices in 70 a saddle 20 secured as shown, to the outlet box.

From the construction, as shown and described, it is obvious that the walls 11 and 12 are spaced from each other, as shown in the 75 sectional view, and the lugs 21 extend inwardly from the inner wall, forming holding means for the globe 22. There are a plurality of these lugs formed in the manner described, and in one place in this double, 80 spaced wall, I have provided registering orifices 23 and 24 to receive the cam-shaped lever 25 which is secured to the reflector flange through the medium of an upwardly extending shaft 26 mounted, rotatably, in 85 the metal strap 27, the shaft being held on tension by the coil spring 28, mounted as shown.

The cam-shaped lever terminates, outwardly, in a convenient end for moving it, 90 and the cam shaft 26, rotatably, the tension of the spring tending to force the outwardly extending end of the cam lever inwardly.

When my device is formed of metal, the 95 lugs 21 and the various orifices hereinbefore described are all formed during the stamping, so that my reflector flange is formed at a minimum of expense.

In practical operation, the horizontal part 10 functions as a reflecting medium for all 100 of the light rays which impinge thereon, and redirect them downwardly through the globe 22 to the working plane. The globe 22 is preferably formed of translucent glass. Globes varying slightly in their neck size 105 may be mounted to my reflector flange as the cam-shaped lever will account for a limited adjustment. Also, the weight of the glass of the globe is not on the spring 28 but is on the eccentric clip which passes through 110

the orifices or slots 23 and 24 and on the lugs 21.

Instead of forming the lugs 21 by perforating the inner wall 11 and pushing the cut portion downwardly to form the lug, registering screw-threaded orifices may be provided in the sides 11 and 12 and globe securing screws secured therein, the double walls 11 and 12 forming means to hold each screw rigidly in its horizontal position. This means of securing the globe is illustrated in the modified form, the screws being designated by the numeral 29. When these screws are used, it would be unnecessary to employ the cam-shaped lever, the cam shaft, the mounting therefor and the coil spring, as the holding screws would each be adjustable.

It is obvious from the above description that I have produced a lighting unit wherein the canopy, reflector, globe securing means, socket securing means and means to secure the canopy to the outlet box are all combined in one piece and extremely simple, and that the functioning of the reflector plate will operate to redirect the upwardly extending rays to the working plane.

Having thus described by invention what I claim and desire to secure by Letters Patent of the United States is:

1. A canopy reflector for lighting fixtures, formed of one piece of metal stamped to provide a central horizontal portion to function as a reflector and an inner and outer spaced wall depending below the reflecting portion, said reflecting portion having an orifice centrally located therein to receive a lamp socket, and means associated with the canopy reflector to secure it to an outlet box,

and means in the depending walls to secure a lighting globe.

2. In a combination canopy and reflector provided with spaced walls depending from the reflector, which walls connect the reflector to the canopy, a plurality of lugs formed on the inner wall thereof, and a spring actuated cam-shaped lug mounted between the said walls, all of said lugs being adapted to receive and hold in place a lighting globe.

3. A combination canopy, reflector, and globe holding means, comprising a stamping formed of one piece of metal to provide a reflector element, a wall depending below the reflector element, a second wall spaced from the first wall, lugs formed on the depending wall, a spring actuated lug mounted between the depending wall and its companion spaced wall, all of the lugs being designed to engage a globe and secure it in position on the canopy reflector, and means to secure the canopy reflector to an outlet box.

4. A combination canopy, reflector, and globe holding means, comprising a stamping formed of one piece of metal to provide a reflector element, a wall depending below the reflector element, a second wall spaced from the first wall, lugs formed on the depending wall, a spring actuated lug, cam-shaped in formation, mounted between the depending wall and its companion spaced wall, all of the lugs being designed to engage a globe and secure it in position on the canopy reflector, and means to secure the canopy reflector to an outlet box.

CHARLES G. LOHMAN.
